UNITED STATES PATENT OFFICE.

ARVE ROBERT MCCANTS AND ALEXANDER JACKSON CORNETT, OF SHREVEPORT, LOUISIANA.

VALVE LIFTER.

Application filed May 3, 1923. Serial No. 636,400.

To all whom it may concern:

Be it known that we, ARVE ROBERT MCCANTS and ALEXANDER JACKSON CORNETT, citizens of the United States, residing at 5 Shreveport, in the parish of Caddo and State of Louisiana, have invented certain new and useful Improvements in Valve Lifters; and we do hereby declare the following to be a full, clear, and exact description of the invention, such as will enable others skilled in the art to which it appertains to make and use the same.

The present invention relates to improvements in valve spring lifters in which provision is made for compressing valve springs on automobile or other motors whenever the valves are to be ground or the valves, valve spring or other parts are to be replaced.

An object of the invention is to provide 20 an improved tool which will afford ease and convenience in the compressing of the valve spring to the end that the lock may be pulled out freely.

Another object of the invention resides in 25 providing an improved valve spring lifter or compressor in which the parts will be so constructed and arranged as to make the device adaptable for substantially all of the motors of different makes now in existence 30 and the device consists in an improved lever peculiarly constructed to embrace the lower part of the spring and the spring collar and to embrace a number of the convolutions of the springs not only in a circumferential but also in an axial direction 35 without interfering with the movement of the lever but affording a better purchase upon the spring.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a fragmentary end view of the motor with the head removed and showing the improved implement in place.

Figure 2 is a similar view showing a subsequent position of the lever with the spring compressed, and

Figure 3 is a perspective view of the improved device.

Referring more particularly to the draw-

ings, the device consists of a lever having an elongated shank 4 tapering toward its handle portion by which it is gripped in the hand of the operator during the act of compressing the valve spring which is indicated at 2 and which surrounds the valve stem 3 in the usual way.

The valve spring is supported at its lower end by a collar 7 which takes against a locking pin or washer 8 extending through or interlocking with the lower end of the valve stem 6. The motor block is indicated at 9 and the head bolts 10 are shown as projecting upwardly therefrom and the head is removed which is required when grinding the valves and removing the carbon.

The lever 4 is provided with a head 5 at its working end, which end is enlarged by virtue of the taper given the shank and this head 5 is substantially semicircular in form 75 and extends in substantial alignment with the plane of the handle 4. The inner semicircular wall 6 of the head is of a contour corresponding generally to the curvature of the coil spring 5, the radius on which the arc 80 6 is struck being slightly greater than radii of the coil spring 5 in order to effect a certain looseness in the fit of the lever upon the spring as is desirable in securing a free movement of the lever from the position 85 shown in Figure 1 to that indicated in Figure 2. Figure 1 and Figure 2 are comparative views in this respect and they show substantially the arc described by the lever from its initial to its final movement 90 in compressing the spring 5 and in freeing the collar 7 from the locking part 8.

The semicircular arms of the head carry at their outer free ends depending lugs 11 and 12 of an elongated character which project at substantially right angles to the plane of the head 5 and to the plane of the handle and such lugs carry inwardly projecting flanges 13 and 14 having inner edges 15 of a beveled character in which the bevel 100 takes place from the upper inner edge downwardly and outwardly. The lugs 13 and 14 are adapted to engage beneath diametrically opposite points upon the spring collar 7 and enable the lever to obtain a purchase thereon 105 and the beveled character of the edges 15 facilitates the engagement of the tool beneath said valve collar and they assist in prying the collar up from the locking element 8. The lugs 11 and 12 extend for a 110

considerable distance axially along the coil spring 5 and the relatively small upper face of the lugs 13 and 14 enable the device to readily pivot upon the collar 7 as indicated in Figure 1.

The lever is supported and afforded a fulcrum by the use of a chain 16 provided at its lower end with a loop 17 adapted to slidably fit upon the handle of the lever to provide 10 a shifting pivotal point therefor which may be changed and varied from time to time in accordance with the operator or the force or tension of the spring. The chain 16 may be composed of any number of suitable links 15 to the upper end of which is attached the hook 18 adapted to engage a head bolt 10 of the motor directly above the valve spring at the time being operated on. The hook 18 will be a prescribed distance from the 20 loop 17 to enable the device to fit easily and freely upon motors of a well known make such for instance as Dodges, Fords, etc. on which the mechanic using the tool is apt to have considerable work and the tool is 25 thus ready for use on this type of motor by simply slipping the open hook 18 about the head bolt 10, it being found that the lever will then assume a correct position with respect to the valve spring. In addition further chain links 19 may be added 30 to the hook 18 and I have shown one such link which will lengthen the chain and make the device adaptable for use in connection with other larger motors. Any number of further links may be added and the link 19 may be prevented from escaping through the open mouth of the hook 18 as by a bead 20 upon said hook 18. The additional link 19 has a loop as shown for fitting over the head bolt of the motor. In such case the hook 18 is not engaged with the head bolt, but forms merely a part of the chain.

In the use of the device the hook or other part of the chain is engaged with a head bolt 10 of the motor and the head of the lever is engaged beneath a spring collar and spring as shown in Figure 1. The fulcrum loop 17 is shifted to a convenient position and the weight of the operator is put upon the handle 5 causing the lever to assume the position shown in Figure 2 which results in the compressing of the spring and the spring collar. The locking element 8 may be then removed 55 and the valve may be lifted up without any interference from the spring.

It will be appreciated that due to the

head construction of the lever, the greatest facility is afforded in grasping the spring and the spring collar and due to the elongated character of the lugs 11 and 12 and the relatively high position at which the head 60 5 engages the coil spring, a substantial part of the spring will be embraced in the device and the lever will not be apt to get in between the convolutions of the spring nor to 65 slip out sidewise or beneath the collar 7. The tool is simple and inexpensive and may be readily carried about in a substantially 70 small space.

It is obvious that various changes and modifications may be made in the details of construction and design of the above specifically described embodiment of this invention without departing from the spirit thereof, such changes and modifications being restricted only by the scope of the following 75 claims.

What is claimed is:—

1. A valve spring lifter comprising a lever 80 composed of a handle having an enlarged head with a semicircular inner wall adapted to embrace the valve spring, lugs projecting at substantially right angles down from the outer free ends of the semicircular wall, said lugs being elongated and having flanges projecting inwardly toward one another and having relatively small upper areas with beveled inner edges and means to support said lever and to provide a fulcrum therefor.

2. A valve spring lifter comprising a lever 85 composed of an elongated and tapering handle having its smaller end outmost and provided at its larger end with a head having a semicircular inner wall slightly greater than the cylindrical valve spring, lugs depending at substantially right angles from the plane of said head and said handle and being elongated to space the head well 90 above the base of the valve spring, said lugs having inwardly extending relatively short flanges having beveled inner ends tapering outwardly and downwardly, said flanges adapted to engage beneath the valve collar, 95 and a chain having a loop slidable upon said lever with a hook at the upper end of the chain adapted to engage about the head bolt of a motor, and an additional chain link upon said hook, said hook having means 100 to hold the additional chain link thereon.

ARVE ROBERT McCANTS.
ALEXANDER JACKSON CORNETT.
